tion of Switzerland

Application May 27, 1947, Serial No. 750,663
In Switzerland July 29, 1946

4 Claims. (Cl. 242—35.6)

1

This invention relates to devices for delivering the threads from a number of cops or the like successively and joined together end to end. Such devices may be used to furnish threads to spoolers, so called; that is to say, machines which take the threads from a number of cops joined end to end and wind them into larger packages of corresponding long thread lengths. Speaking generally however my thread-furnishing device can be used to furnish thread to any machine that may require such long lengths of thread as it is capable of providing.

It is to be understood that the term cop is used in this specification and its claims in a generic sense; that is to say, regardless of whether the thread package is cone shaped or otherwise, and regardless of whether the thread is wound and carried on a pirn, spool, spindle, tube, cone etc., or is hollow wound.

Speaking generally the thread delivering or 20 thread furnishing device of my invention involves a rotatable member, in which a number of cops are placed and which carries them successively to an unwinding position, a thread-tying mechanism, and a device for bringing into tying relation the end portion of the thread of an unwound or nearly unwound cop and with the starting end of the thread of the cop that is next to be unwound. The whole may be controlled by a 25 feeler finger engaging whatever cop is being unwound at the moment. When used in connection with a spooler, for example, both the thread furnisher and the spooler can be controlled cooperatively by a single control mechanism. Additional cops can be supplied to the thread furnisher from time to time and thereby thread of any length whatsoever can be delivered by the furnisher.

The accompanying drawings illustrate a preferred form of my invention. In these drawings Fig. 1 is a side elevation of the rotatable mechanism, the controller or gear box and the tying mechanism. Fig. 2 shows a substantially transverse section of the same apparatus. Fig. 3 is a plan view of it, the arrow showing the direction of rotation. Fig. 4 is a longitudinal section of the gear box of Fig. 1, and Fig. 5 is a plan view of the box. Fig. 6 is an elevation showing the side of the gear box opposite to that shown in Fig. 1. Fig. 7 is a section of the gear box adjacent the side shown in Fig. 6. Fig. 8 illustrates the positioning of two threads ready for tying, and Fig. 9 illustrates the same threads after tying and cutting. Fig. 10 is a side elevation of a modified form of gear box in which the feeler acts through solely mechanical means. Fig. 11 is a

2

side elevation illustrating the preferred cooperative relation between the furnishing device of Fig. 1 and a spooler.

In the controller or gear box 1 is rotatably mounted a control shaft 2 on which are rigidly mounted a drum 3 having a cam groove and also two cam disks 4 and 5. On the control shaft 2 is mounted also a driver sleeve 7, which is free to rotate on the shaft and which carries a ratchet or teeth 6; on a portion 8 of sleeve 7 is fixed a pulley 9. A pin 10 projects from one end of the grooved drum 3 and carries a pawl 11 to engage teeth 6 on the sleeve 7; a spring 12 tends to press the pawl to the teeth 6 (Fig. 7). A finger or catch 13, fixed to a shaft 14 that is journaled in the gear box 1, holds the pawl 11 out of engagement with teeth 6 on sleeve 7 (Fig. 7) whenever thread is being drawn from a cop carried by the device.

A column 16 projects from the cover 15 of the gear box; it may be screwed into the cover and an end 17 of the column projecting into the gear box may serve as a bearing for an arm 18. A ring 19 on the end 17 may hold the arm on the column end. On the arm 18 is fixed a pin 20 carrying, rotatably, a cam roller 21 engaging in the cam groove 22 of the drum 3. The cam groove 22 is so shaped (see Fig. 2) that during a brief interval, once in each rotation of the drum 3, the groove causes the arm 18 to oscillate, i. e. swing through the arc α (Fig. 5) and return it to its initial position. The arm 18 projects out of cover 15 through an aperture 23, and inserted in the arm 18, reciprocatably, is a driver pin 24 which is pressed outwardly from the arm at all times by spring 25. Also inserted in cover 15, reciprocatably, is a locking pin 26 which is continuously pressed in the same direction by spring 27.

On column 16 is rotatably mounted a tube 28 to which are fitted, at its bottom, a plate 29, or rotatable member having a number of positions for cops and serving to carry cops, and at its top a thread-guide or eye-and-clamp carrying member 30. The tube 28, plate 29 and thread-guide 30 constitute what I call the "revolving box." The lower face of plate 29 is provided with a ring of teeth 38 which are engaged by the driver pin 24 and locking pin 26; the driver pin 24 turns the revolving box step by step as the arm 18 is oscillated and the locking pin 26 prevents the box being turned backward. To the top face of plate 29 are rigidly fixed, at regular intervals, cop holders 31 on which are set the cops 32 from which the thread is to be taken. The thread-guide 30 is provided with a radial

thread-guiding slot 33 for each cop 32 (preferably on the end of an individual radial arm as shown), and wires 37, one for each slot 33 and each having one end fixed to the guide 30 at 35 and its other end crossing its slot (Fig. 3) and unattached to permit the thread to have access to its slot, and serve to retain the threads in the slots. The slots 33 and the wires 37 are thread guiding means and provide a thread guiding eye for each cop. Also spring plates 36, one for each cop 32 of the revolving box and each attached at one end at 35 to the guide 30 i. e. adjacent to the path of the movement of the thread guiding eyes, and serve as clamps for the respective threads by pressing the threads to the face of the guide. The spring plates or eyes 36 and the thread-guiding eyes 33 are in substantially the same rotational plane as will be seen from the drawing. Above the thread-guide 30 a ring 39, fixed to the column 16, carries a stationary finger or thread-catching hook 40, that extends radially outwardly to the cop unwinding station 65 with its thread engaging area at about the position whereat the threads are drawn from the box, i. e. adjacent thereto, but more advanced in the direction of the rotation of the plate 29 than said path of the unwinding threads. The thread engaging area of the hook is also adjacent to the path of the movement of the thread guiding eyes so as to be close thereto.

In gear box 1 is oscillatably mounted a shaft 41 on which are fixed, inside gear box 1, an arm 42 resting on the edge of the cam disk 4 and, outside the gear box 1, a stirrup 43 having an arm 44 projecting upwardly therefrom. The cam disk 4 is so shaped that once in each rotation of shaft 2 (Fig. 1), and at appropriate times as appears hereafter, it acts on the arm 42 to oscillate shaft 41 and thereby swing the upwardly extending arm 44 substantially toward the axis of the revolving box. At the top end of arm 44 is mounted a thread-tying mechanism 45 which may be of conventional design or another design suitable for the purpose. As briefly illustrated here the thread-tying mechanism has a casing 46 containing moving parts of the mechanism, two thread guides 47 and 48 extending from the casing 46 and between which is mounted the knoter 49, and, on the rear of casing 46, an operating lever 50. Also to the uppermost part of arm 44 is fixed a bolt 51 on which a lever 52, to contact with the operating lever 50, is swivelingly seated. To one arm of lever 52 is articulated a rod 53 which is connected at its lower end by an articulation to an arm 54.

At the rear part of gear box 1 is oscillatably mounted a shaft 55 (Figs. 4 and 5) on which are fixed, outside gear box 1, the arm 54 and, inside gear box 1, an arm 56 carrying a pin 57, on which is mounted roller 58 engaging in the cam groove 22 of drum 3.

A feeler 59 is fixed to a pin 60 that is free to turn in the lower end of the arm 44, and contacts the particular cop that at the moment is at the position, 65, at which the cops are unwound. On the pin 60 is fixed also an arm 61 that carries a contact that is connected to a conductor 62 which leads to two electromagnets 63 (Figs. 5 and 6) and 64 (Fig. 11) which are connected to one side of an electrical supply circuit. The contact on arm 61 is arranged to engage with an insulated screw 66, when permitted to do so, and this screw is connected by conductor 67 to the opposite side of the supply circuit. On the shaft 14, outside gear box 1, is mounted an arm

68 that is attracted by the magnet 63 and thus rocks 14 when this magnet is energized (Fig. 6). When the magnet 63 is not energized, the arm 68 falls by its own weight and turns shaft 14 in the opposite direction. This latter movement causes locking pawl 13, also fixed on said shaft, to swing inward into the path of the hose 69 on driver pawl 11, and thus disengage the latter from the ratchet or teeth 6. This disconnects the control shaft 2 from the drive sleeve 7 and permits the shaft 2 and the parts connected to it to come to and remain at rest despite the fact that their drive sleeve 7 may be rotating. The parts are in these positions while a cop, at 65, is being unwound.

Also at one side of the gear box 1 is fixed a bolt 70 (Fig. 5) on which is hinged a lever 71 carrying a pin 72 having a cam follower roller 73 mounted on it (Fig. 2). This roller 73 contacts cam disk 5. To this lever 71 is articulated a connecting rod 74. This mechanism serves to correlate the thread furnishing device, i. e. the revolving box and its associated mechanism, with whatever machine may be supplied with thread by the revolving box.

Fig. 11 illustrates the correlation of the revolving box, gear box and control mechanism and the tying mechanism with a spooler which I prefer. Conventionally a spooler consists of some frame members 75 carrying brackets 77 on which are supported, side by side, a number of more or less independently operating spooler mechanisms such as 78. I provide one thread furnishing device, i. e. revolving box and associated mechanism, for each spooler mechanism. Each is mounted substantially in front of the spooler mechanism which it supplies, and the group may be mounted on some brackets 76 also carried by the spooler frame members 75. Fig. 11 illustrates one spooler mechanism 78 and its associated furnishing device, the remainder being assumed to be behind those shown.

The spooler mechanism 78 illustrated (like each of the others of the machine) is driven in a conventional manner by means of friction wheels 79 and 80 from a shaft 81 serving, say, all the spooler mechanisms of the machine. These friction wheels drive a roller 82 of the respective mechanisms 78, which causes the package 83 into which the thread is being wound at 78, to rotate while a thread guide 84, moving to and fro, directs the thread to the growing package or spool. The spooler mechanism 78 can be started and stopped by the movement of its starting lever 85. When freed, the starting lever is drawn to its inoperative or mechanism-stopping position by a spring 86, and is held in its operating position by a locking device. The locking device comprises a hook 87 mounted on the starting lever 85 and a locking lever 89 which has a hook 88 to cooperate with hook 87. The locking lever 89 is pivoted at 94 on a side wall of the spooler mechanism 78. When the two hooks are engaged the starting lever 85 is held in operating position. During the winding or spooling process, the locking lever 89 is held in locking position by a stop motion arm 90 affixed to 89 and which normally is held, in its position shown, by the thread 91 passing over it on its way to the spooler. As soon as such pull is interrupted however, as when the thread breaks and thus releases arm 90, this arm and the locking lever 89 are rotated counterclockwise as seen in Fig. 11, by gravity, and therewith the hook 88 falls away from hook 87 and spring 86 turns

the starting lever 85 to its inoperative position. Additionally the locking lever 89 is provided with an armature 92 for the electromagnet 64, so that the locking lever is rotated to disengage 88 from 87 when the magnet is energized and thus caused to attract the armature 92. Accordingly the locking device is able to stop the spooling mechanism both when a rupture of the thread occurs and when it becomes necessary to bring a new cop into thread-delivering position. A lower shoulder 93 on locking lever 89 serves to lift the latter into locking position when the spooler is started anew. This result is attained by arranging the hook 87 on the starting lever 85 to press the shoulder 93 downward so as to engage hook 88 with hook 87 whenever the starting lever 85 is returned to starting position. The spooler mechanism is started automatically whenever a new cop is brought to thread-delivery position by so disposing the cam disk 5 that this disk swings lever 71 downward at such times and connecting the connecting rod 74 to the starting lever as shown.

The revolving box and its associated mechanism are driven from the shaft 95 (which may be rotated continuously) by means of a pulley 96 fixed on it and a belt 97, running over this pulley and the pulley 9 (Figs. 2 and 5) on the driver sleeve 7.

The mechanism of my invention, including the connection of the furnisher to a spooler shown in Fig. 11, operates in the following manner: Cops 32 to be unwound are placed on the cop holders 31 of plate 29, and the free end of the thread 34 of each cop is pulled into or through the respectively adjacent slot 33 of the guide 30, the guide wires 37 facilitating the threading and preventing the threads 34 from springing out of slots 33 again. The end of the thread 34 of each cop (excepting the cop that is at the station 65 whereat the unwinding occurs) is then pulled beneath the clamping spring 36 that is respectively adjacent the next preceding slot in the direction in which the revolving box rotates (see Fig. 3), and thus is clamped at this place, and is cut off, say by a sharp edge of clamping spring 36. The thread 98 of the cop at the station 65 however, after being pulled through its slot 33, is carried across the finger or thread-catcher 40, and then up over the thread guide 99 and the stop motion member 90 and through the thread guide 84, and wound, say a few times, on the spool 83. This being an entirely new start, the mechanism is brought into motion by turning the starting lever 85 to starting position by hand; the same is true following each rupture of the thread. The parts are then in the positions shown in Fig. 11, and from thence on the operations are automatic. The cop at station 65 is first unwound until there remains only a small ring 100 of thread (Fig. 8) on, say, its spindle (designated 101 by Fig. 8). Because it is no longer supported by thread the feeler 59 now falls so far as to bring the contact of lever 61 against the contact screw 66 so that the electromagnets 63 and 64 are energized. As already described, the energization of the electromagnet 64 releases hook 88 from hook 87, the lever 85 shifts, and accordingly the spool 83 ceases to rotate. At the same time the energization of the magnet 63 releases the pawl 11, Fig. 7, and the shaft 2 starts to revolve. The consequent rotation of the grooved drum 3 and cam disks 4 and 5 thereon results in the following series of operations: Lever 18, because its cam roller 21 engages within

the cam groove 22 in drum 3, swings through the angle α (Fig. 5) and back again, and this, acting through the driver pin 24, turns the revolving box to bring the next cop in order toward working position, i. e. unwinding station 65 (or 65a in Fig. 8). However the thread 102 from, say, the spindle 101 of the nearly unwound cop is engaged and kept hook by the stationary thread catch-back 40 and is restrained against movement with the thread guiding eye of the unwound cop, e. g. 101, as the turning of the box moves the unwound cop, e. g. 101, from position 65, so that this thread 102 comes to lie substantially side by side with thread 103 of the cop newly moved to position 65, i. e. in a position favorable for the tying of the two together. This result occurs because the positions of the thread catching hook 40, the clamps 36, and the path of the movements of the thread guiding eyes and the unwinding thread of the cop at the unwinding station 65, are related to each other as previously described.

Thereupon the further rotation of cam disk 4, acting through arm 42, shaft 41 and stirrup 43, causes arm 44 with the thread-tying mechanism 45 thereon to swing toward the axis of the revolving box between the adjacent two radial arms 104 and 105 of the thread-guide 30, at about the position 65. In the course of this movement the threads 102 and 103 are caught by thread guides 47 and 48 of thread-tying mechanism 45, and so guided that they are seized and knotted together by knotter 49, which in the meantime has been actuated from cam groove 22 in drum 3 through arms 56 and 54, rod 53, lever 52 and the operating lever 50. Knotter 49 also cuts off the thread ends behind the knot 106 (Fig. 9). Continued rotation of cam disk 4 then causes the thread-tying mechanism 45 to swing back to its initial position. The spooler 78 then is caused to start operation again by the disk 5 pressing down on the lever 71 to draw down the connecting rod 74 to restore the starting lever 85 to its operating position and reengage the holding hooks 87 and 88. The cam disk 5 then rotates slightly further until the shift lever 71 is released by it, in order that at the next cop change, or in case of rupture of the thread, the lever 71 will be able to move upward along with the starting lever 85.

In the meantime the current supply to the electromagnets 63 and 64 has been interrupted by the feeler 59 which is again contacting a wound cop at station 65. Therefore the locking pawl 13 has been swung inward. However the rotation of shaft 2 and its cams continues until the revolution of the pawl 11 again brings its nose 69 (Fig. 7) against the locking pawl 13, and as a result the driver pawl 11 is disengaged. When this happens the control shaft 2 with its control members comes to rest. The winding or spooling operations at the spooler mechanism 78 now continue until the cop newly brought to position 65 is almost completely unwound, and when this happens the operations described above are repeated, and thereafter will be repeated again and again until the supply of cops in the revolving box is exhausted, or will continue indefinitely if the revolving box is kept supplied with wound cops.

As before indicated, in Fig. 10 is shown a modification of my invention in which the cop feeler acts through mechanical means rather than electrical contacts. In this case the feeler 59a is provided with a locking pawl 107. A locking lever 108 pivoted on a bracket 109, remains in contact with pawl 107 as long as feeler 59a is prevented

by unwinding cop 65 from dropping down. The arm 410 of the locking lever 408 is provided with a pin 411 engaging into a slot 412 of a lever 413 that is fixed on shaft 44a. This shaft can be assumed to perform the same functions as the shaft 14 of the earlier figures. To lever 413 is articulated also a rod 414, which may be, for example, articulated to arm 92 of locking lever 39 (Fig. 11). When cop 65 is unwound to such an extent that feeler 63a is able to drop and thereby release the locking lever 408, lever 413 falls and, acting through 414, brings spooler 48 to a stop by drawing down the locking lever 39 and thereby freeing hook 87 from hook 88 as before. The lever 413 in dropping also, acting through shaft 44a, corresponding to 14, turns the locking pawl 43, Fig. 7, thereby freeing the pawl 41 so that this driving pawl engages a tooth 6 on rotating sleeve 7 and brings the control shaft 2 into action. The subsequent actions will then be quite like those described before, as will be understood.

It will be understood that my invention is not limited to the details of construction and operation described above and shown in the drawings, except as appears hereafter in the claims.

I claim:

1. A thread furnishing mechanism comprising a rotatable member having a plurality of positions for cops to carry cops to an unwinding station successively, a thread-guiding eye for each of said plurality of cop positions, a thread clamp for each of said eyes to hold the starting end of a thread extending from its respectively associated eye, said eyes and clamps being connected to said rotatable member for movement therewith, means to rotate said rotatable member before a cop at the unwinding station has been completely unwound to bring another cop to the unwinding station and to advance the incompletely unwound cop to another station beyond the unwinding station, each of said eyes and its associated clamp being so related that a thread extending from an eye associated with a cop position at said unwinding station to its respective clamp is adjacent the thread extending from an incompletely unwound cop at said another station, and a thread tier to tie threads extending from said two stations, said tier being disposed adjacent the place where the threads are so adjacent.

2. The subject matter of claim 1, characterized by the fact that means are provided, located to the rear of said another station, to engage thread of an incompletely unwound cop at said another station, and the eyes and their clamps

are so related that a thread extending from an eye associated with a cop position at the unwinding station to its respective clamp is adjacent a thread extended from said means to an incompletely unwound cop at said another station.

3. A thread furnishing mechanism comprising a rotatable member having a plurality of positions for cops to carry cops to an unwinding station successively and including an eye-and-clamp carrying member, said carrying member providing an eye for each of said plurality of cop positions to guide threads being unwound at the respectively associated cop positions and also providing adjacent each eye a clamp adapted to hold the end of a thread extending from the eye behind it, said eyes and clamps being disposed in substantially the same rotational plane, means to rotate said rotatable member to bring cop positions thereof to the unwinding station successively and move them therebeyond, a feeler to feel cops at the unwinding station and effective before a cop being unwound at the unwinding station is completely unwound to bring said means into action to rotate said member to bring a cop position with a filled cop to the unwinding station and move a cop position at the unwinding station with an incompletely unwound cop to another station beyond, means to hold adjacent an eye at the unwinding station thread of an incompletely unwound cop extending from the eye at said another station, a thread extending from an incompletely unwound cop at said another station thereby being placed adjacent a thread of a filled cop extending from an eye at the unwinding station to its respectively associated clamp, and a thread tier adjacent the place where threads are thus brought together to tie said threads.

4. The subject matter of claim 3, characterized by the fact that said means to hold thread of an incompletely unwound cop is a stationary member standing in the path of movement of a thread of an incompletely unwound cop as the latter moves from the unwinding station toward said another station.
